UNITED STATES PATENT OFFICE.

HARRY TONKS, OF EAST ORANGE, NEW JERSEY, ASSIGNOR OF ONE-HALF TO THOMAS TONKS, OF NEWARK, NEW JERSEY.

BUTTON-GRINDING MACHINE.

Application filed February 27, 1923. Serial No. 621,587.

To all whom it may concern:

Be it known that I, HARRY TONKS, a citizen of the United States, and residing at East Orange, in the county of Essex and State of New Jersey, have invented a new and Improved Button-Grinding Machine, of which the following specification is a full disclosure.

This invention appertains to grinding machines and it relates more especially to automatic mechanism for ornamenting blanks in the process of making buttons therefrom.

In the manufacture of buttons, it is frequently desirable to cut in the blanks a circular groove for the purpose of providing finished buttons with a predetermined configuration. For example, certain types of button have their faces provided with a circular shallow groove which materially improves the appearance of the button. The substance used in making buttons is relatively hard and this ornamentation is therefore cut by means of a grinding wheel or the like and the operation has heretofore been performed on the successive blanks quite laboriously and with much loss of time by hand.

A primary object of this invention is to render available an instrumentality of an automatic character capable of forming the blanks as aforesaid in rapid succession and of doing so in a more uniform and precise manner than has heretofore been possible. In a machine of this character, it is proposed to provide means for conveying the button-blanks in continuous succession past the region of operations and to provide an automatic instrumentality which shall, during the transit of said blanks, operate thereupon without losing time through stoppage to cut in the face of each blank a shallow circular groove accurately concentric with the blank and of uniform depth and character.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this

disclosure and, in such drawings, like characters of reference denote corresponding parts throughout all the views, of which:—

Fig. 1 is a side-elevation of a mechanism embodying the several characteristics of this invention. Fig. 2 is a plan of so much of the mechanism as suffices to disclose the structure and mode of operation of the invention. Fig. 3 is a fragmentary plan showing the position of the grinding mechanism at the conclusion of its operation on one blank and preparatory to automatically returning for the purpose of resuming its operation on the next blank of the traveling train. Fig. 4 is a detail showing a fragmentary section through line 4—4 of Fig. 2 and depicting the grinding wheel in operating relation to a blank held in a traveling chuck. Fig. 5 is a plan of a blank preparatory to being operated upon and Fig. 6 and 7, respectively, are plans and diametral sections of a blank after treatment.

Referring to the drawings, 1 indicates a roulette having a hub 2 whereby it is mounted for rotation about a vertical shaft 3. This roulette 1 has a series of circumferential seats 4 which are adapted to engage annular portions 5 of a series of traveling chucks. These chucks are each journaled in collars 6 which form parts of an endless chain; said collars being pivotally connected by links 7 which engage pins seated in ears 8 extending radially from the collars 6. The upper ends of the chucks are formed to provide so-called collets 9 which are adapted to receive and firmly retain the flat disk-like blanks 10 to be converted into buttons; it being unnecessary to dwell upon the specific details of construction of the chucks inasmuch as they conform to the conventional type for holding blanks for various operations.

In this mechanism, the chucks, in the form of an endless chain pass continuously around the roulette 1 and, as they come into engagement with the said roulette, they are firmly held and accurately positioned by virtue of the tension of the chain of chucks and the engagement of each individual chuck with its corresponding seat 4 provided by the roulette.

Mounted on the frame of the machine is a segmental platform 11 which may be secured in place in any desirable manner, as,

for example, by the split-clamp 12 grasping the pillar 13 forming a part of the main frame. Arranged on this segmental platform is a track 14 which is curved concentrically with the axis of the center shaft 3 and, slidably arranged on the track 14 is a reciprocating table 15 which is normally held against a bumper 16 by means of a contractile spring 17; this representing the initial position of the grinding mechanism whereby it is ready to be brought into operative relation with a blank to be formed.

The grinding element is a small cylinder 18 of abrasive material having its periphery formed with a small flange 19 which latter cuts the groove; the remaining portion of the periphery of the cylinder being available, if desired, for polishing and grinding the face of the blank. This grinding element is mounted on the extremity of a shaft 20 which may in turn be driven by an electric motor 21 or a pulley 22, according to preference. The frame in which the shaft 20 is mounted is preferably mounted 25 adjustably with relation to the reciprocating table 15 as, for example, by having a tongue-and-groove connection with an intermediate part 23 which in turn has a transverse tongue-and-groove connection 30 with a standard 24 uprising from the table 15. An adjusting screw 25 enables the frame of the shaft 20 to be horizontally shifted towards and away from the center of the blank. The intermediate element 23 is at all times freely slidable in a vertical direction in the upright member 24; the accuracy of the movement being regulatable by the conventional gib positioned by screws 26.

40 It may be explained that at the moment of bringing a blank directly under the grinding element 18, it is necessary that said element should be somewhat elevated to prevent any damage to the parts and, to that end, a lifting cam 27 is secured to the stationary segmental platform 11 and is adapted to support a lower roller 28 (see Fig. 1) mounted on a leg 29 which is secured to the intermediate member 23.

50 When the parts are positioned, as aforesaid, the traveling clamps can pass underneath the forward extremity of the shaft 20, including the grinding element 18 without any interference with the blank but, the 55 instant the blank is directly underneath the grinding element 18, there goes into action an instrumentality which advances the grinding mechanism at the same rate of travel as the blank is advancing and during this travel the grinding element is lowered on to the face of the blank to cut or fashion the same and, at the end of that operation, is raised to clear the blank and, while raised and out of contact with any 60 blank, it is returned to the position shown

by Fig. 1. The instrumentality for effecting these operations comprises a series of spokes 30 which are secured to the roulette by bolts 31 and are spaced angularly apart in correspondence with the angular distance 70 between the centers of the successive chucks as they travel around the periphery of the roulette. The forward extremity of each spoke is adapted to engage a suitable catch carried by the traveling grinding mechanism. As shown by Fig. 2, the forward end 32 of the spoke is in engagement with the extremity 33 of a small lever pivoted at 34 to a shelf 35 mounted on post 36 extending upwardly from the traveling table 15. 75 A control lever is likewise pivoted at 37 to the same shelf and the contractile spring 38 normally holds these parts in the position shown by Fig. 2 so that the end 39 of the last-mentioned lever acts trigger-like to prevent any rotation of the other lever. A stop-pin 40 determines the extent to which the spring 38 may move the trigger lever. It will be seen, therefore, that when the end 80 32 of the spoke 30 engages the extension 33 85 it will positively cause the traveling table 15 to advance against the pull of the spring 15 and at the same angular rate as the blank secured in the collet directly under the grinding wheel 18. Initially, however, 90 there is no contact between the two last-mentioned parts by reason of the operation of the cam 27 but very shortly the roller 28 will ride down the incline shown at the forward end of the cam and the grinding element and parts associated therewith will descend to establish contact between the grinding wheel 18 and the blank in the collet chuck. The extent to which this descent may take place is, in turn, controlled 95 by an adjustable stop 41 and the speed of the descent is cushioned by a spring 42 as will be understood by Figs. 1 and 4. During the aforesaid advance of the platform 15, the grinding operation will be accomplished and thereupon it becomes necessary to elevate the grinding wheel and return it to its initial position. This elevation is accomplished by means of two cams 43 and 44 100 which are adjustably mounted on posts extending upwardly from the stationary platform 11 and which have their ends bevelled to receive rollers 45 and 46 mounted at the upper portion of the intermediate member 23. When these rollers ride on to the aforesaid cams, they lift the grinding wheel entirely clear of the blank and after this has 105 been effected, a stop-pin 47 comes into contact with the trigger-like lever pivoted at 37 and such lever is released from the other lever which thereupon is free to swing and to disengage itself from the spoke causing the advance of the grinding mechanism. Thereupon, the spring 17 pulls back the traveling table 15 quickly until it is 110 115 120 125 130 135

rested by the bumper 16. During the intermediate part of the return travel of the grinding mechanism, the parts may descend but without any effect inasmuch as no blank 5 is at that time in the region of the travel and before the parts are drawn back to their initial position, the roller 28 engages the cam 27 and elevates the grinding wheel so that it will not interfere with the forward 10 movement of the next on-coming blank.

This cycle repeats itself successively as each blank arrives into the region of activity. In order that the grinding wheel may cut a circular groove, a belt 48 travels 15 around an idle pulley 49 and thence into contact with the pulleys 50 provided by each traveling chuck and, since these chucks are rotably mounted in their supports, the belt will cause the chucks, together with 20 the blanks, to rotate during the period of contact with the grinding wheel and those circular grooves of the nature specified will be cut.

It will be perceived from the foregoing 25 that this mechanism is comparatively simple in structure and that it functions to form each blank in turn during its transit and without necessitating any stoppage in the travel of the blank so that, in consequence, 30 the mechanism is capable of quantity production and in an entirely automatic manner will continuously operate on a succession of blanks to produce the desired result.

Without further analysis, the foregoing 35 will so fully reveal the gist of this invention that others can, by applying current knowledge, readily adapt it for various utilizations by retaining one or more of the 40 essential characteristics of either the generic or specific aspects of this invention, and, therefore, such adaptations should be, and are intended to be, comprehended within the meaning and range of equivalency of the 45 following claims.

Having thus revealed this invention, I claim as new and desire to secure the following combinations and elements, or equivalents thereof, by Letters Patent of the 50 United States:

1. A machine of the nature disclosed combining a roulette; a train of chucks adapted to be engaged and held firmly by said roulette; a support reciprocatable in an arc 55 concentric with said roulette; a tool located by said support adjacent the path of the blanks held by said chucks; means movable with the train of chucks for causing said support to advance at the same angular rate 60 as said roulette when each chuck registers with said tool; means for establishing contact between said tool and the blank in said chuck during the advance of said support; means for rotating said chuck during the 65 period of contact; and means for terminat-

ing said contact and restoring said support to its initial position.

2. A grinding-machine combining a train of travelling chucks; a grinding tool normally positioned in offset relation to the path of travel of the blanks conveyed by said chucks; means to rotate said tool; means operative when the blank attains a predetermined relation to said tool for causing said tool to travel in coincidence with the path of said blank and for establishing contact between said blank and said tool to effect a grinding operation during a portion of the stroke of said tool; and means for quickly returning said tool while out of contact 75 with said blank to its initial position.

3. A machine of the nature disclosed combining a reciprocatable support; a tool mounted on said support; means for elevating said tool relative to said support during the end-periods of the stroke of said support, and for depressing said tool during 80 the intermediate portion of the stroke of said support; and chuck mechanism adapted 85 to maintain a blank in contact with said tool during the depression of the latter.

4. A button-forming machine combining a continually rotating roulette; a train of blank-retaining chucks adapted to travel around with said roulette; a rotating-tool 90 normally positioned above the path of travel of the blanks; a support for said tool movable concentrically with said roulette; a member movable with said roulette and adapted to engage said support to advance 100 it when a blank comes into registry with said tool; and means for shifting said tool into engagement with said blank during a portion of the travel of said support.

5. A grinding-machine combining a train 105 of travelling chucks; a tool normally positioned in offset relation to the path of travel of the blanks conveyed by said chucks; means operative when the blank attains a predetermined relation to said tool for causing said tool to travel in coincidence with the path of said blank and for establishing contact between said blank and said tool during a portion of the stroke of said tool; means for rotating said chucks when in registry with said tool; and means for quickly returning said tool while out of contact 110 with said blank to its initial position.

6. A machine of the nature disclosed combining a reciprocatable support; a tool mounted on said support; means for elevating said tool relative to said support during the end periods of the stroke of said support, and for depressing said tool during the intermediate portion of the stroke of said support; and mechanism including a rotating chuck adapted to rotate and maintain a blank in contact with said tool during the depression of the latter.

7. A button-forming machine combining a 130

- continually rotating roulette; a train of blank-containing chucks adapted to travel around with said roulette; means for rotating said chucks while revolving said roulette; a rotating tool normally positioned above the path of travel of the blanks; a support for said tool revoluble concentrically with said roulette; a member rotatable with said roulette and adapted to engage said support to advance it when a blank comes into registry with said tool; and means for shifting said tool into contact with said blank during a portion of the travel of said support.
- 15 8. A grinding-machine combining a train of travelling chucks; a grinding tool normally positioned in offset relation to the path of travel of the blanks conveyed by said chucks; means operative when the blank attains a predetermined relation to said tool for causing said tool to travel in coincidence with the path of said blank and for establishing contact between said blank and said tool during a portion of the stroke of said tool; means adjacent the extreme positions of said tool for raising said tool out of contact with said blank; a detent device for rendering said tool translating means inoperative at the end of the stroke of the tool; and means for quickly returning said tool while out of contact with said blank to its initial position.
- 20 9. A machine of the nature disclosed combining a reciprocatable support; a tool mount-
ed on said support; means for elevating said tool relative to said support during the end periods of the stroke of said support, and for depressing said tool during the intermediate portion of the stroke of said support; travelling chuck mechanism adapted to maintain a blank in contact with said tool during the depression of the latter; and a detent device operative to effect the return-stroke of said tool.
- 25 10. A button-forming machine combining a continually rotating roulette; a train of blank containing chucks adapted to travel around with said roulette; a rotating tool normally positioned above the path of travel of the blanks; a support for said tool movable concentrically with said roulette; a detent; a member movable with said roulette and adapted to engage said detent to advance said support when a blank comes into registry with said tool; means for shifting said tool into engagement with said blank during a portion of the travel of said support; and a trip for disengaging said detent at the end of the working-stroke of said support.
- 30 In witness whereof, I hereunto subscribe my name, as attested by the two subscribing witnesses.
